INVENTOR:

UNITED STATES PATENT OFFICE.

BARTHA L. WOODWARD, OF IRON MOUNTAIN, MICHIGAN.

HAIR-CURLER.

1,084,776.

Specification of Letters Patent. Patented Jan. 20, 1914.

Application filed April 17, 1912. Serial No. 691,290.

To all whom it may concern:

Be it known that I, BARTHA L. WOODWARD, a citizen of the United States of America, and a resident of Iron Mountain, county of 5 Dickinson, State of Michigan, have invented certain new and useful Improvements in Hair-Curlers, of which the following is a specification.

The main objects of this invention are to 10 provide an improved form of hair curler of the kind adapted to have a lock of hair coiled or wound thereon and secured thereby and allowed to remain for a certain length of time, whereby the hair becomes 15 curled; to provide an improved hair curler of this kind which is adapted to be dampened so as to impart moisture to the hair and thereby facilitate the setting of the curl; to provide improved means for confining the ends of the hairs in the lock to 20 render the coiling of the lock more easy; and to provide a curler of this kind which is simple and inexpensive in construction.

An illustrative embodiment of this invention is shown in the accompanying drawings in which:

Figure 1 is a front view of a curler constructed according to this invention. Fig. 2 is a side view of the same. Fig. 3 is a view 30 similar to Fig. 1 but showing a lock of hair with its end inserted between the flaps preparatory to rolling. Fig. 4 is a side view of the same. Fig. 5 is a detail showing the ends of the curler bent over, after the hair 35 has been rolled up in the curler, for securing the curler to the coil of hair.

In the construction shown in the drawings, a piece of limp fabric or other suitable material 1 is folded upon itself and stitched 40 at 2 parallel to the fold so as to provide the casing 3 and the flaps 4 and 5. A pliable core 6 is inserted in the casing 3, preferably in the form of rubber covered copper wire.

When the curler is to be used the cloth is 45 moistened and the end of a lock of hair 7 is placed between the flaps 4 and 5 and rolled or coiled with the cloth around the core 6. The function of the flap 5 is to confine the ends of the hairs, to keep them spread out,

and to insure the proper and easy rolling of 50 the lock. When the entire lock of hair has been wound on the curler as close to the head as is practical, the ends of the rolled curler are bent over, as shown in Fig. 4, in which position they are retained by virtue 55 of the pliable core 6. The moisture in the cloth dampens the hair and facilitates the setting of the curl therein, the curler being allowed to remain with the lock of hair coiled thereon for such a time as is necessary, as, for instance, over night. For numerous reasons it is obviously preferable to wet only that part of the hair which is to be 60 curled, than to wet all of the hair as is sometimes done when curls are formed by 65 means of the usual curl papers and the like. When it is desired to remove the curler the ends are straightened and the coil of hair uncoiled from the curler and removed therefrom. 70

Although but one specific embodiment of this invention has been herein shown and described, it will be understood that numerous details of the construction shown may be altered or omitted without departing 75 from the spirit of this invention as defined by the following claims.

I claim:

1. A hair curler comprising a strip of fabric folded upon itself and stitched parallel to said fold to form a casing and a pair of flaps, a pliable reinforcing core housed in said casing, said curler being adapted to have the ends of a lock of hair placed between said flaps and coiled upon 80 said core and secured thereto by the bending of said core. 85

2. A hair curler comprising a strip of limp material folded upon itself and stitched parallel to said fold to form a casing and a pair of superimposed flaps on one side thereof, one of said flaps being of greater length than the other, a pliable reinforcing core housed in said casing, said curler being adapted to receive the ends of hair to be curled between said flaps for curling upon said core and to be secured by bending of said core. 90 95

3. A hair curler, comprising a sheet of limp material having one end folded back upon itself and secured so as to provide two superimposed flaps and a pliable member secured to said sheet adjacent to the fold, said flaps being adapted to receive a lock of hair between them for rolling up therein, and said pliable member being adapted for

bending to secure the curler in its rolled condition.

Signed at Iron Mountain this 14th day of April 1912.

BARTHA L. WOODWARD.
